INTERNAL COMBUSTION ENGINE

Christian J. Hug, Highland, Ill.

Application January 14, 1939, Serial No. 250,862

8 Claims. (Cl. 123—50)

My invention relates to an internal combustion engine and more particularly to that type of engine which comprises a fixed cylinder cooperating with an oppositely reciprocating cylinder and a piston connected to a double-throw crankshaft.

One object of my invention is to provide means for injecting liquid fuel through the head of the movable cylinder so that it will operate as a "Diesel" engine of the two-stroke cycle type.

10 Another object of my invention is to provide an injection pump in cooperation with the fuel nozzle, which pump is actuated by the movement of the reciprocating cylinder with reference to a relatively fixed part of the engine; and further 15 to provide manually-operated means for controlling and automatic means for limiting the action of the pump and the consequent speed of the engine.

Another object of my invention is to provide 20 an improved form of pre-combustion chamber, thus insuring the quick starting of the engine.

A further object of my invention is to construct the movable cylinder or sleeve with a completely closed end, the air inlet and exhaust ports 25 being both positioned adjacent the opposite or open end of the sleeve and thus obviating the necessity of compression seals for the outside of the sleeve.

My invention also consists of various other 30 novel features and details of construction, all of which are described in the following specification and pointed out in the claims.

In the accompanying drawings which illustrate one form of internal combustion engine made in 35 accordance with my invention Figure 1 is a vertical section, the piston and movable cylinder being shown at the outer limit of their strokes; Figure 2 is a vertical section taken at right angles to Figure 1 and showing the piston and movable cylinder at the inner end of their strokes; Figure 40 40 is an enlarged section through the fixed head and adjacent parts; Figure 4 is a bottom plan view of some of the parts shown in Figure 3; Figure 5 is a section taken at right angles to Figure 3; Figure 6 is an enlarged sectional detail view of the nozzle and pump; Figure 7 is a section taken on the line 7—7 of Figure 6; Figure 8 is a horizontal section through the fixed and movable cylinders; and Figure 9 is a section taken on the line 9—9 of Figure 5.

Referring first to Figures 1 and 2, the numeral 10 indicates the engine casing or housing. For convenience in illustration, this housing is shown as enclosing a single power unit. It will be understood, however, that in practice a plu-

rality of units will usually be included in a single housing. The housing is provided near its upper end with a fixed head 11 to which is attached, by screws 12, the flange 13 of the stationary cylinder 14. Sliding within the cylinder 14 is the movable cylinder 15. Within the latter is the piston 16. Cylinder 15 and piston 16 are connected to a double-throw crankshaft 17 by connecting rods 18 and 19, respectively. The crankshaft is preferably so proportioned that the throw of the piston will be about twice that of the cylinder. In Figure 1 I have shown the crank arms so arranged that the piston has an angular lead over the cylinder in which case the engine should run so as to turn the crankshaft 15 in the direction indicated by the arrow. The crank arms may, however, be arranged at an angle of 180 degrees in which case the engine will run equally well in either direction.

The upper end of cylinder 15 is closed by a head which, for convenience of manufacture, is formed of two parts 20 and 21 secured together by screws 22 (Figure 3). The space between the part 21 and the closed end of cylinder 15 forms an air compression chamber 24. Air enters this chamber through a port 25 communicating with the air intake pipe 26 and is discharged through a port 27. The walls of cylinder 14 are supported by horizontal diaphragms 28, 29 and 30. The inner edges of these diaphragms are turned over where they contact with the cylinder and are curved adjacent such turned over part as best shown in Figure 3. This imparts a certain resiliency to the diaphragm to compensate for expansion of the cylinder. Cylinder 15 is provided with an enlarged portion 31 which forms with the diaphragm 30, a second air compression chamber 32. The enlarged portion 31 may bear upon the walls of the engine housing or upon an auxiliary guide 33. Formed in cylinder 14 are one or more air inlet ports 34 and outlet ports 35 adapted to register with inlet and outlet ports 36 and 37, respectively, in cylinder 15 when the parts are in the position shown in Figure 1. Compressed air from chamber 32 is admitted to the inlet ports through a port 38 in diaphragm 30 and from chamber 24 through port 27 and ports 39 in diaphragms 28 and 29. A flap valve 40 is positioned adjacent the inlet ports to prevent back pressure. Air from ports 35 and 37 is discharged through exhaust pipe 41. To facilitate the cooling of cylinder 15, I provide its periphery with a number of annular fins 15' and form in the cylinder 14, openings 14' through which the said fins are exposed to the surrounding atmosphere 55

to dissipate the heat generated by combustion in said cylinder 15.

Formed in the part 20 of the cylinder head is the precombustion chamber 42 containing an ignition element 43 in the form of a coil. One end of this coil is connected to a spring finger 44 (Figure 3) adapted to engage with a contact 45 when the cylinder is at the upper end of its stroke. Current is supplied by a conductor 46. It will be understood that the other end of the coil is grounded on the machine. The contacts are preferably protected by a dome 47. The pre-combustion chamber communicates with the main combustion chamber 49 between the movable cylinder head and the piston by a central opening 50 and a plurality of tangential openings 51 positioned around the central opening. The pre-combustion chamber is surrounded by an air cell 52 which communicates with the openings 51.

An injection nozzle 53 discharges fuel into the pre-combustion chamber. As shown in the drawings, this nozzle is of the well-known "Bosch" type and need not be described in detail. It will be understood, however, that other types of nozzles may be employed. The nozzle is carried in the lower end 54 of a plunger 54, which end is threaded or otherwise secured in the part 21 of the cylinder head. This plunger slides in a guide sleeve 55 carried by the head of cylinder 14. In order to provide a floating bearing permitting self alignment of the plunger, the sleeve is not directly mounted in the head but is carried by a flange member 56. Between this flange member and the head, a gasket 57 of rubber or other resilient material is interposed and the parts are secured together by bolts 58 passing through oversize openings in the flange member.

Secured in the upper end of plunger 54 is a reduced extension 59 having a central bore 60 at its lower end and a larger bore 61 at its upper end. Mounted in bore 60 is the inner or feed plunger 62 having an enlarged head 63 working in bore 61. A coil spring 64 is positioned in bore 61 below head 63 to normally hold the inner plunger in raised position relative to the outer plunger and thus provide a fuel chamber 65 (Figure 6) below plunger 62. Adjacent this chamber, part 59 is provided with a pair of short bores 66 and 67. Bore 66 communicates at its upper end through a port 68 with the fuel inlet 69 and near its lower end with the fuel chamber 65 through port 70. This bore also communicates with nozzle 53 through a fuel passage 71. Bore 67 communicates with the interior of the nozzle 53 by a by-pass 72. The bores 66 and 67 are connected by an annular groove 73. A spring-pressed ball valve 74 prevents back pressure from the nozzle forcing the fuel through port 68 and a similar ball valve 75 prevents pressure in chamber 65 from forcing fuel through the by-pass. A cup packing 76 prevents fuel from being forced around the plunger into bore 61.

It will be seen that when cylinder 15 moves downwardly it will carry with it both the outer 65 and inner plungers. During this travel it is necessary to move the inner plunger downwardly with relation to the outer plunger in order to force fuel through the nozzle. To accomplish this, I secure to the extension 59 of the outer 70 plunger, a bracket 77 to which is pivoted at 78, an arm 79. The inner end of this arm bears on the end of the plunger head 63 and its outer end cooperates with a cam or eccentric 80. This cam is mounted on a stud 81 and its position is varied 75 by crank arm 82 and throttle rod 83. Stud 81

is mounted in one end of a bell-crank lever 84 pivoted at 85 to a bracket 86 carried on sleeve 55. The other end of the bell-crank lever engages a rod 87 pivotally mounted on sleeve 55. The rod is surrounded at each side of the lever arm by a coil spring 88. The tension of these springs may be adjusted by a nut 89. Mounted on arm 79 is a resilient support 90 carrying an adjustable weight 91. It is desirable that the speed of travel of plunger 62 be increased at the lower end of its stroke. To accomplish this I form on arm 79, a projection 92 with which the cam engages at the end of the stroke to cause such increase in speed.

Formed in part 20 of the cylinder head is a 15 secondary air chamber 92 (Figure 5) communicating with the main combustion chamber 49 through a port 93 which may be opened or closed by a conical plug valve 94. This valve is carried by a stem 95 extending up through a sleeve 96. On the upper end of the stem is a block 97 between which and the end of the sleeve a coil spring 98 is interposed to maintain the surfaces of the valve in close contact. On the block is a laterally projecting pin 99 which engages with a vertical slot in a U-shaped member 100. This member is carried on a control lever 101 sliding in a guide 102. When the engine is being started, lever 101, which extends to the exterior of the housing, is moved into position to close the valve, thus securing the maximum compression in the main combustion chamber. After running condition is attained, lever 101 is moved to open the valve and place the secondary air chamber in communication with the main combustion chamber which will appreciably reduce the compression in the latter.

The operation of my engine is briefly as follows. Assuming the parts to be in the positions shown in Figure 1, rotation of the crankshaft will cause cylinder 15 to move downwardly and piston 16 to move upwardly, thus closing the inlet and exhaust ports and compressing the air in chamber 49. During the downward stroke of cylinder 15, the movement of arm 79 on its pivot 78, resulting from its contact with cam 80, will cause plunger 62 to move downwardly with relation to the outer plunger and thus force fuel from chamber 65 through passage 71 to the nozzle from which it is discharged into the pre-combustion chamber. When the parts have assumed the position shown in Figure 2, the charge is fired. In starting the engine this is accomplished by coil 43. While current is supplied to the coil only at the upper end of the cylinder stroke, it will retain its temperature a sufficient length of time to accomplish the desired result. After running condition is attained, current is discontinued from the coil as the engine will be fired from heat of compression alone as is usual with the "Diesel" type of engine. Starting of the engine is facilitated by the particular form of pre-combustion chamber employed. The tangential openings 51 cause the air entering the chamber through them from the main combustion chamber to have a whirling or turbulent motion which causes it to mix thoroughly with the fuel discharged from the nozzle. The air cell 52 surrounding the pre-combustion chamber not only insulates it to retain the heat therein but furnishes a reserve supply of air to be discharged into the main combustion chamber to further the combustion of fuel therein.

The speed of the engine is controlled by movement of cam 89 to vary the stroke of plunger 62 75

relative to the outer plunger and consequently the amount of fuel forced out of chamber 65 to the nozzle at each stroke. To limit the speed of the engine, the cam is mounted on the bell-crank lever so that after a predetermined speed is reached, the inertia of the parts will overcome the tension of springs 88 and permit the lever 84 to move on its pivot 85 to reduce the piston stroke. This result is further assisted by the use of the adjustable weight 81 which exerts a damping effect on the arm 79.

While the fuel may be fed to the pump by gravity, the outer plunger 54 will act as the piston of a low pressure pump to raise the fuel from a lower level. The double plunger construction, therefore, functions as a combined low and high pressure pump. The excess fuel drawn in by the low pressure pump is returned to the fuel supply and the amount of pressure therein is regulated by the usual pressure valve.

Having fully described my invention, what I claim as new and desire to secure by Letters Patent of the United States is:

1. An internal combustion engine comprising cooperating piston and cylinder elements each of which reciprocates, a fuel injecting nozzle carried by and movable with one of said elements, a fuel injecting plunger actuated by the movement of said element, and means for adjusting the stroke of said plunger, said means comprising an actuating element adjustable during operation of the engine.

2. An internal combustion engine comprising cooperating piston and cylinder elements each of which reciprocates, a fuel injecting nozzle carried by and movable with one of said elements, a fuel injecting plunger actuated by the movement of said element, means for adjusting the stroke of said plunger, said means comprising an actuating element adjustable during operation of the engine, and means responsive to the engine speed in excess of a predetermined rate for automatically limiting the amount of fuel supplied to the engine.

3. An internal combustion engine comprising piston and cylinder elements each of which reciprocates, a fuel injection nozzle carried by and movable with one of said elements, fuel pumping means for the nozzle including a pair of plungers one sliding in the other, a pivoted arm carried by one plunger and bearing on the other, an adjustable element variably operating

said arm, and a resiliently mounted support for said element.

4. An internal combustion engine comprising cooperating piston and cylinder elements each of which reciprocates, a fuel injecting nozzle carried by and movable with one of said elements, fuel pumping means for the nozzle including a pair of plungers one sliding in the other, a pivoted arm carried by the outer plunger and bearing on the inner plunger, an adjustable actuating element variably operating said arm, and a resiliently mounted support for said element.

5. An internal combustion engine comprising piston and cylinder elements each of which reciprocates, a fuel injection nozzle carried by and movable with one of said elements, fuel pumping means for the nozzle including a pair of plungers one sliding in the other, a pivoted arm carried by one plunger and bearing on the other, a weight adjustably mounted on said arm, and an adjustable actuating element variably operating said arm.

6. An internal combustion engine comprising cooperating piston and cylinder elements each of which reciprocates, a fuel injecting nozzle carried by and movable with one of said elements, fuel pumping means for the nozzle including a pair of plungers one sliding in the other, a pivoted arm carried by the outer plunger and bearing on the inner plunger, a flexible bar on said arm, a weight carried by said bar, and an adjustable actuating element variably actuating said arm.

7. An internal combustion engine comprising cooperating piston and cylinder elements each of which reciprocates, a fuel injecting nozzle carried by one of said elements, said nozzle including a plunger passing through a fixed head, and a guide for said plunger resiliently carried by the head to permit self alignment of the nozzle carrying part with a supporting member.

8. An internal combustion engine comprising cooperating piston and cylinder elements each of which reciprocates, a stationary cylinder in which said reciprocating cylinder moves, a fuel injecting nozzle carried by the movable cylinder, said nozzle including a plunger passing through the head of the stationary cylinder, and a guide for the plunger resiliently carried by said head to permit self alignment of the stationary and reciprocating cylinders.

CHRISTIAN J. HUG.
